Primary Examiner — Anhdao Doan(74) *Attorney, Agent, or Firm* — Kilpatrick Townsend & Stockton LLP(57) **CLAIM**

The ornamental design for an implantable pulse generator external charger, as shown and described.

DESCRIPTION

FIG. 1 is a perspective view of an implantable pulse generator external charger.

FIG. 2 is another perspective view of the charger of FIG. 1; and,

FIG. 3 is a side view of the charger of FIG. 1.

The broken lines illustrate portions of the implantable pulse generator external charger that form no part of the claimed design.
